UNITED STATES PATENT OFFICE

2,163,380

AUTOMOBILE REFLECTOR

Fred Malaguti, Plymouth, Mass.

Application August 27, 1937, Serial No. 161,199
Renewed January 6, 1939

3 Claims. (Cl. 88—81)

My present invention relates to reflectors, and more particularly to reflectors for use on automobile bumpers, mudguards and the like either front or rear for the purpose of warning approaching vehicles of the presence of the vehicle. This is particularly of value when an automobile has been parked and the lights have failed to stay lighted in the absence of the owner or driver, also when the automobile is operating without one light without the knowledge of the operator.

The principal object of my invention is therefore an improved reflector for automobiles;

Another object is an improved means of constructing an automobile reflector which provides simple dust and moisture proof reflector surfaces, and

Other objects and novel features comprising the construction and operation of my device will appear as the description of the same progresses.

Referring to the drawing illustrating the preferred embodiment of my invention,

Fig. 1 is a front elevation of the reflector;

Fig. 2 is a cross-section taken on the line 2—2 of Fig. 1;

Fig. 3 is front elevation of the reflector plate;

Fig. 4 is a greatly exaggerated fragmentary cross-section of one of the reflector surfaces indicated at 4—4 in Fig. 3, and

Fig. 5 is a detail of the clamping bolt.

Referring more in detail to the drawing, 10 indicates the front and side casing in which are positioned a plurality of openings 11. Directly under the front side of casing 10 I have placed a flat sheet 12 of colored glass or Celluloid. The drawing indicates red, but any color may be used as the occasion requires. Back of the colored glass 12 I have placed a reflector plate 13 about the surface of which are positioned a plurality of depressed reflector surfaces 14. These reflector surfaces are highly polished nickel plated metal. Silvered surfaces may be used if desired but in my device polished nickel serves the same purpose and will maintain its brilliancy over long periods of time due to the fact that these surfaces and depressed areas in the plate 13 are tightly sealed from dust, moisture and air currents. The plate 13 is formed in a die and it will be noted that around the rim of each reflector surface I have provided a knife-like projection 15 which fits against the colored glass or Celluloid tightly, and where Celluloid, which I prefer, is used, this knife-like edge presses into the Celluloid surface making a very tight seal. To obtain this tight seal, I have provided a back

plate 16 which engages inside the side edges of the casing 10. When the apparatus is assembled the back plate 16 is firmly pressed in place compressing the back of the depressed reflector units tightly against the Celluloid 12 after which the telescopied edges of the back plate 16 and casing 10 are secured by solder or welding. In the center of the back plate 16 I have provided a depressed area in which I have placed a nut 17 for the purpose of clamping the various parts 10 together by means of a carriage bolt 18. The square shank of the bolt 18 passes through square openings 19 provided in the outer casing 10 and the reflector plate 13, a similar opening also being provided in the Celluloid plate 12 and back plate 16. The nut 17 is screwed down tight against the shoulder of the bolt 18 and due to the fact that the sides of the back plate 16 are secured in the sides of the casing 10 additional pressure is brought to bear on the back 20 of the curved reflector members 14 thereby compressing them more firmly against the Celluloid plate 12. This pressure is resilient to a certain degree due to the fact that the depressed portion at the center of the back plate 16 is not bottomed against the reflector plate 13. In this construction the knife-like edges 15 are maintained in a spring compressed relation with the Celluloid or glass member 12. The reflector is mounted on the bumper or other part of the automobile by means of the bolt and wing-nut 18 in the manner shown in Fig. 2, 20 indicating a bumper in cross-section.

Having thus described my invention what I claim as new is:

1. A reflector for automobiles and the like comprising in combination, a casing having a front wall and side walls, a plurality of circular openings in said front wall, a soft, colored transparent plate located against the back surface of said front wall and covering said openings in said wall, a second plate located adjacent the back surface of said transparent plate, a plurality of cup-shaped depressions formed in said second plate and located in register with the openings in said front wall, said cup-shaped depressions being provided with reflector surfaces on the sides thereof adjacent said transparent plate, annular projections having sharp edges formed around the rims of the said cup-shaped depressions, said annular projections being engaged in the adjacent surface of said soft transparent plate, a back plate having side flanges adapted to engage inside said side walls, a depression formed in the central portion of said back plate,

- 5 a bolt hole located in the central portion of said depression in said back plate, bolt openings located through said front wall, transparent plate, and second plate and in alignment with the opening in said back plate depression, a bolt located through said bolt hole and bolt openings, a nut located on said bolt in said back plate depression, said nut being adapted to engage against the back surface of said back plate depression and engage the inner surface of said back plate tightly against the back surfaces of the cup-shaped depressions of said second plate, means for attaching said reflector to the bumper of an automobile.
- 10 2. A reflector for automobiles and the like comprising in combination, a casing having a front wall and side walls, a plurality of circular openings in said front wall, a soft, colored transparent plate located back of said front wall and covering said openings, a reflector plate located back of said transparent plate, the reflector area of said reflector plate comprising a plurality of depressions aligned with said circular openings the concaved surfaces of which comprise reflector surfaces, annular rims having sharp edges located around the peripheries of said depre-

- 20
- 25

sions, a back plate engaging against the convexed sides of said depressions, means for clamping said front wall and back plate firmly together for the purpose of engaging said annular rims against the soft transparent plate. 5

3. A reflector for automobiles and the like comprising in combination, a casing having a front wall and side walls, a plurality of circular openings in said front wall, a back casing having side flanges engaging within said side walls, a reflector plate provided with a plurality of depressed cups in alignment with said circular openings, the concaved sides of said cups comprising reflector surfaces, the convexed sides of said cups engaging against the inner side of said 15 back casing, a soft, transparent plate located between said reflector plate and said front wall, annular rims having sharp edges located around said reflector cups adjacent said transparent plate, annular recesses located in the side of said 20 transparent plate adjacent said annular rims, means passing through said front wall, transparent plate, reflector plate and back casing adapted to tightly engage said annular rims in said annular recesses. 25

FRED MALAGUTI.
